REFRIGERATION UNIT

Paul H. Maffet, La Junta, Colo.

Application July 31, 1939, Serial No. 287,527

4 Claims. (Cl. 62—8)

This invention relates to a refrigeration unit and more particularly to a device which will replace the usual float valve thermostatic expansion valve of the typical refrigerating equipment.

5 In the usual mechanical refrigerating system a float valve is employed to control the flow of refrigerant liquid to the evaporator or cooling unit. A thermostatically controlled expansion valve is also employed to control the flow of refrigerant. Both of these valves are subjected in both their various moving parts and in their valve seats which require frequent repairs and replacements. The float valve is also objectionable in that its operation is not uniform, that is, it will remain closed while the liquid refrigerant is collecting until it rises over the top of the float. The float then suddenly releases the valve to allow a large flow of refrigerant which will continue until the refrigerant passes out when it suddenly closes. This results in an uneven, fluctuating flow of refrigerant and a wide variance of pressure differential.

25 The principal object of this invention is to eliminate the float valve and the thermostatic expansion valve with their attendant maintenance costs and their non-uniform operation; to provide means which will maintain a uniform pressure differential between the high and the low pressure zones of the system throughout the entire range of operation; and in which all wearing and moving parts will be eliminated so that it can operate continuously and indefinitely without requiring repairs or replacements.

35 Other objects of the invention are to provide a combination expansion valve, receiver, and condensing unit for refrigerating systems which will lower operating costs, which will operate on lower head pressure, which will require less condensing coil surface, and in which all wearing parts will be eliminated.

40 Other objects and advantages reside in the detail construction of the invention, which is designed for simplicity, economy, and efficiency. These will become more apparent from the following description.

45 In the following detailed description of the invention reference is had to the accompanying drawings which form a part hereof. Like numerals refer to like parts in all views of the drawings and throughout the description.

In the drawings:

50 Fig. 1 is a cycle diagram of a typical refrigerating system illustrating the improved unit in place therein.

Fig. 2 is an enlarged vertical section through the improved unit.

Fig. 3 is a vertical cross section therethrough, taken on the line 3—3, Fig. 2.

Fig. 4 is a horizontal section, taken on the line 5 4—4, Fig. 2.

In the cycle diagram of Fig. 1, the typical elements of a refrigerating system are designated by numeral as follows; electric motor 10, compressor 11, condenser 12, evaporator or cooler 13 10 and receiver 39. This invention is designed to be placed in the line between the receiver 39 and the evaporator 13.

The invention comprises a horizontal housing 14, sealed to and supporting a vertical housing 15. 15 The housing 15 is entirely sealed but access may be obtained to the housing 14 through a removable head plate 16 which is secured thereon by means of suitable clamp bolts 17. The vertical housing 15 contains a heat exchange coil 18 spirally wrapped about its inner surface. One extremity of this coil is connected to a tube 19 leading from the receiver 39. The other extremity of the coil is connected with a by-pass tube 20 communicating through the head plate 16 of the 25 housing 14.

The interior of the housing 15 communicates at its top to a suction line 21 leading to the intake of the compressor 11, and communicates adjacent its bottom with a gas line 22 leading 30 from the evaporator 13. By this arrangement, the entire interior of the housing 15 is constantly filled with cold, low-pressure gas.

The by-pass line 20 leads to a screen fitting 23 supporting a suitable screen 24. The screen fit- 35 ting 23 is threaded into an expansion valve coupling 25 containing an orifice member 26 having a restricted flow orifice. The orifice member discharges into an injector tube 27 extending through the head 16. The injector tube 27 ter- 40 minates within a suction sleeve 28 which is supported from the head 16 by means of an outer supporting tube 29 provided with perforations 30. The supporting tube 29 carries a fitting 31 at its inward extremity from which a trap coil 45 32 is supported.

A quantity of fluid 33, such as mercury or other fluid agent of greater specific gravity or density than the refrigerant, sufficient to partially cover the coil 32, is contained within the housing 14. 50 The fluid 33 is free to flow through the perforations 30 into the interior of the tubes 28 and 29 and into the fitting 31. The extremity of the trap coil 32, shown at 34, opens to the interior of the housing 14 adjacent the bottom thereof. 55

A gooseneck trap 35 extends through the top of the housing 15 through the latter and into the housing 14 to a point below the surface of the fluid therein. The gooseneck is perforated, 5 as shown at 36, at a point above the normal fluid level in the housing 14. A drain tube 37 drains the trap of the gooseneck back into the body of fluid in the housing 14. A liquid refrigerant line 38 extends from the gooseneck 35 to the evaporator 18.

Operation

Let us start the cycle at the compressor 11. The compressor compresses the refrigerant gas to a liquid. This liquid is first cooled in the condenser 12 from whence it flows through the coil 18. The latter is immersed in cold, low pressure gas so that a second condensation or chilling takes place therein. The cool liquid now flows to the expansion orifice member 26 from which it expands to a wet gas in the injector tube 27. The velocity of the refrigerant discharging from the tube 27 creates a suction in the suction tube 28 to draw the fluid 33 from the container 14. 20 This fluid and the refrigerant flows through the trap coil 32 chilling the fluid 33. From the extremity of the coil, the refrigerant bubbles up through the fluid 33 and flows into the gooseneck 35 where a portion of the fluid being carried by 25 the cold expanded gas is dropped and flows back to the container 14 through the drain tube 37. The refrigerant gas will collect at the top of the housing 14 where it will rapidly condense and fall to the surface of the fluid 33. From 30 thence it will flow through the perforations 36 into the flow line. The cold refrigerant gas intermixed with the remainder of the fluid 33 then flows through the line 38 to the evaporator 13 where the major expansion, evaporation and 35 cooling takes place. The expanded gas then returns through the line 22 to the housing 15 where it absorbs heat from the coil 18 and thence flows back to the compressor 11.

As long as the unit and the evaporator are 40 warm, the viscosity or density of the fluid 33 is low and the gas can readily flow through the fluid and can readily draw it into the suction tube. As the evaporator gets colder, however, the gas returning therefrom has a lower temperature 45 which acts to lower the temperature of the refrigerant flowing through the coil 32. This results in lowering the temperature of the fluid 33 so that the latter becomes more dense and it is more difficult for the gas to pass therethrough. Thus the flow of the refrigerant to the evaporator is increasingly resisted as the temperature 50 thereof drops and the pressure in the receiver gradually builds up so as to maintain a uniform pressure differential between the liquid refrigerant from the compressor and the gas in the evaporator.

As the temperature rises in the evaporator, the 55 temperature of the gas returning therefrom will correspondingly rise. This will raise the temperature of the fluid 33 to decrease its density and to allow more refrigerant to flow to the evaporator.

It will be noted that the acceleration and 60 deceleration changes are very slow and very gradual so that the desired temperature can be accurately maintained without the violent fluctuations of a float or thermostatic valve. The flow is at all times accurately and minutely proportional to the variations of temperature in the 65 system. This control does depend upon the

amount of refrigerant present and is accomplished without the use of valves or other moving parts.

It is possible to approximate the results accomplished by this invention by connecting the line 5 38 directly to the extremity 34 of the coil 32 so that the refrigerant will not come in actual contact with the fluid 33. The refrigerant liquid will then collect in the lower portions of the turns of the coil and act to resist the flow of refrigerant therethrough in accordance with the density produced therein by the chilling effect of the fluid 33.

While a specific form of the improvement has been described and illustrated herein, it is desired 15 to be understood that the same may be varied, within the scope of the appended claims, without departing from the spirit of the invention.

Having thus described the invention, what is claimed and desired secured by Letters Patent is: 20

1. Means for controlling the flow of refrigerant to the evaporator of a refrigerating system comprising: a fluid container; a fluid of greater density than the refrigerant in said container; a refrigerant coil partially submerged in said fluid; means for conducting refrigerant to said coil, said coil discharging below the surface of the fluid in said container; and means for conducting the refrigerant from above the fluid to 25 said evaporator.

2. Means for controlling the flow of refrigerant to the evaporator of a refrigerating system comprising: a fluid container; a fluid of greater density than the refrigerant in said container; a pressure jet for introducing refrigerant into 35 said container below the fluid level therein; a sleeve surrounding the pressure jet and opening to the fluid so that the pressure of said jet will draw the fluid into the sleeve to intermix the fluid and the refrigerant; and means for conducting the refrigerant from above the normal 40 fluid level to said evaporator.

3. Means for controlling the flow of refrigerant to the evaporator of a refrigerating system comprising: a fluid container; a fluid of greater 45 density than the refrigerant in said container; a pressure jet for introducing refrigerant into said container below the fluid level therein; a sleeve surrounding the pressure jet and opening to the fluid so that the pressure of said jet will 50 draw the fluid into the sleeve to intermix the fluid and the refrigerant; a coil immersed in said fluid for receiving the intermixed refrigerant and fluid, said coil discharging into said container; and means for conducting the refrigerant 55 from said container to said evaporator.

4. Means for controlling the flow of refrigerant to the evaporator of a refrigerating system comprising: a fluid container; a fluid of greater 60 density than the refrigerant in said container; a pressure jet for introducing refrigerant into said container below the fluid level therein; a sleeve surrounding the pressure jet and opening to the fluid so that the pressure of said jet will 65 draw the fluid into the sleeve to intermix the fluid and the refrigerant; a coil immersed in said fluid for receiving the intermixed refrigerant and fluid, said coil discharging into said container; a trap for separating the fluid from said refrigerant; means for conducting the refrigerant from said container to said evaporator; and a trap for separating the fluid from the refrigerant flowing to said conduit.
